UNITED STATES PATENT OFFICE.

HAROLD McD. BROWN, OF GROTON, NEW YORK, ASSIGNOR TO CORONA TYPEWRITER COMPANY, INC., OF GROTON, NEW YORK, A CORPORATION OF NEW YORK.

TYPEWRITING MACHINE.

Application filed May 13, 1922. Serial No. 560,758.

To all whom it may concern:

Be it known that I, HAROLD McD. BROWN, a citizen of the United States, and resident of Groton, in the county of Tompkins and State of New York, have invented certain new and useful Improvements in Type-writing Machines (Case 184), of which the following is a specification.

This invention relates to improvements in typewriting machines, and more particularly to paper feeding means for such machines.

The invention has for its principal objects to provide simple and efficient means for supporting and guiding a continuous strip or web of paper on the traveling platen carriage of a typewriting machine so that the web may be led from a supply roll to the printing point; to provide means for supporting a roll of paper or a plurality of rolls of paper of the same or different widths, on the platen carriage in such manner that either or all of the rolled strips of paper may be fed to the printing point; to provide a roll-holder for perforated label strips or other rolled webs of paper of light weight and inexpensive construction; to provide simple means for detachably supporting a roll holder on the platen carriage to travel with the carriage; to provide means for preventing accidental spinning or unrolling of the web or webs of paper mounted in the holder; to provide a roll holder and supporting means therefor so constructed that the holder may be securely mounted on the carriage without employing separate fastening or clamping devices and that the roll or web may be mounted in the holder without employing nuts, screws or the like to retain the roll supporting rod or shaft in place; and to provide a detachable roll supporting means so constructed and arranged as not to interfere with the ordinary use of the machine for writing upon sheets when the roll supporting means is attached to the machine.

To the foregoing and other ends, which will hereinafter appear, the invention consists in the improved construction of devices, the arrangements of parts, and combinations of elements, set forth in the following description and particularly pointed out in the appended claims.

The improvements are illustrated in connection with the Corona typewriting ma-

chine, a well known machine of the front-strike type a platen carriage fed step by step for letter-spacing, and a platen supported on the carriage and rotatable for spacing between lines of writing. It will be obvious, however, that the improvements may be employed with other typewriting machines.

In the accompanying drawings, wherein is illustrated one satisfactory and desirable embodiment of the invention, and in which similar reference characters designate corresponding parts throughout the several views:

Figure 1 is a side elevation, partly in vertical section, of a Corona typewriting machine equipped with the improved web supporting and guiding means, the web illustrated being a transversely perforated rolled strip of blank labels;

Fig. 2 a fragmentary front elevation thereof;

Fig. 3 a bottom plan view of the roll supporting and guiding means, in which is indicated by dotted lines the manner of supporting an additional roll in the holder;

Fig. 4 a detail view showing the manner of attaching to the holder frame the shaft and roll holding device illustrated in Fig. 9;

Fig. 5 a detailed sectional view on the line 5—5 of Fig. 7;

Fig. 6 a vertical sectional view of the roll supporting means, taken on the line 6—6 of Fig. 2;

Fig. 7 a detailed sectional view, taken on the same line as Fig. 6, showing the positions of the parts before the roll and its shaft are assembled in the holder frame;

Fig. 8 an end view of a label roll showing the roll of labels loosely mounted on a pencil to revolve about the pencil;

Fig. 9 a perspective view of the detachable device for holding the roll shaft and a roll of labels against endwise displacement and for preventing accidental spinning or unrolling of the roll of labels;

Fig. 10 a bottom plan view, partly in section, showing the holder frame slipped partly on its supporting arms;

Fig. 11 is a sectional view on the line 11—11 of Fig. 7 showing the manner in which the holder frame binds on the supporting arms when it is slipped downward thereon; and

Fig. 12 a detail rear view showing the supporting arms for the holder frame folded downward and inward under the paper apron or table of the typewriting machine.

Referring to the drawings by numerals, 1 designates the platen of a Corona typewriting machine, 2 the platen carriage which is fed step by step transversely of the machine during writing, 3 the paper table or apron mounted on the carriage, 4 the paper feed roller which is rotatably mounted on the forward edge of the paper table, 5 the scale bar which is held to the paper table forward of the feed roller, and 6 the main frame of the machine in which the type-bar action is mounted. The foregoing parts are all of the usual construction.

Two sheet metal brackets 7 are rigidly secured at 8, by spot welding or otherwise, to the rear face of the paper table 3 adjacent the upper edge of the table and near opposite ends of said table. The inner ends of the brackets are offset from the rear face of the paper table, as shown more clearly in Figs. 6 and 10, and two sheet metal bars 9 are pivotally held to the inner offset ends of said brackets by screws 10. Bars 9 are preferably tapered from their pivots toward their free ends. As shown, the inner edges of the bars incline toward the outer edges of the bars from the hinged ends of the bars to the free ends thereof, while the outer edges of the bars are parallel with the longitudinal center lines of the bars, but both side edges of each bar may be inclined toward the longitudinal center line of the bar if desired.

Screws 10 extend loosely through apertures 11 in bars 9 a short distance from the lower ends of the bars to provide short arms 9^a adapted to engage stop lugs 12 on the brackets 7 to arrest the bars in overlapped horizontal position under the paper table when the bars are swung inwardly and downwardly to compacted non-use position, as shown in Fig. 12. Lugs 12 also coact with the longer arms of bars 9, as shown in Figs. 3 and 6, to limit the upward and outward swinging movements of the bars, said stop lugs arresting the bars when they reach a slightly laterally diverging position, as shown in Fig. 3. Bars 9 form foldable supports for a detachable paper or label roll holding frame.

The roll-holding frame is preferably stamped from a single rectangular sheet metal blank and, as shown, comprises longitudinal cross-bars 13 and 14 and integral end-bars 15 and 16. The rear cross-bar 13 is formed with an upstanding flange 17 along its rear edge, and the front cross-bar 14 is formed with an upwardly and forwardly rolled flange 18 along its rear edge and two upstanding lugs or short flanges 19 at each end of the forward edge thereof.

Each of the end bars 15 and 16 is formed with an integral shaft-supporting arm 20 depending from the inner edge thereof. Arms 20 are provided with registering apertures 22 adjacent the lower ends thereof forming end bearings for a roll-supporting shaft or rod 23. As shown, shaft or rod 23 consists of an ordinary lead pencil, thus avoiding the expense of supplying a special metal or other shaft with the roll-supporting attachment, but it will be obvious that any suitable shaft may be employed.

The flange 17 is provided adjacent its ends with two slots 24 in register with slots 25 formed in the short flanges or lugs 19 on cross-bar 14. The slots 24 and 25 are sufficiently wide to receive the arms 9 and are as long as or longer than the greatest width of said arms at least up to a point adjacent the apertures 11 in the arms.

To connect the frame to the paper table, the arms 9 are swung outward and upward until their longitudinal center lines are at right angles to a line through their pivots. The two slots 24 and the two slots 25 are spaced apart longitudinally of the frame a distance equal to the distance between the inner edges of the outer ends of arms 9 when in this position so that the frame may be slipped on the outer ends of the arms as shown in Fig. 10. The inclination of the inner cam edges of the arms 9 is such, however, that as the frame is moved farther downward and forward on the arms, the arms will be cammed outward by the engagement of the inner ends of slots 25 with the inclined inner edges of the arms until the outward movement of the arms is arrested by stops 12, as shown in Fig. 3. The parts are preferably so proportioned that at this time the outer edges of arms 9 will abut against the outer ends of slots 24, as shown more clearly in Fig. 11. As arms 9 are arrested at uniform angles to the axis of the platen by stops 12, the frame, and the axial line of bearing apertures 22 in arms 20 therein, will be parallel with the axis of the platen and a roll or rolls of paper on shaft 23 will be parallel with the platen.

To mount a roll of paper, blank paper labels, or the like, in the frame, the pencil or other shaft or rod 23 is passed through the tubular core or spool 26 upon which the paper web or strip 27 is wound and also through the bearings or apertures 22 in arms 20. The rolled web or paper strip shown consists of a strip of paper printed and perforated transversely to form a series of blank labels. It will be obvious that the device may be employed for supporting any other form of roll or rolls of paper.

For the purposes described below, I prefer to employ one or more of the detachable and adjustable sheet metal arms or members 28. Member 28 is formed with a laterally

bent portion or head 29 at a right angle to the depending main arm portion thereof. Head 29 is formed with an integral rearwardly facing hook lug 30 extending upwardly from the forward edge of the head and two integral forwardly facing hooks or angular lugs 31 extending upwardly from the rear edge of the head. A normally upwardly projecting spring tongue 32 is stamped up from the center of the head 29. Arm 28 is attached to the cross-bar 13 of the frame by engaging hooks 31 over flange 17 adjacent the end bar 15 of the frame, as shown in Fig. 4, then rocking said arm forwardly to pass hook 30 through a notch 33 in the forward edge of bar 13, and then sliding said arm laterally along the bar. Arm 28 is provided adjacent its lower end with a shaft bearing or aperture 34 normally out of register or axial alignment with the apertures 22 in arms 20, as shown in Figs. 7 and 10, but adapted to be moved into register with the apertures 22.

Spring tongue 32 normally holds the upper face of head 29 spaced from bar 13 and holds the upper ends of hooks 30 and 31 against the upper face of bar 13 and the upper edge of flange 17, respectively, as shown in Figs. 5 and 7, when shaft 23 is removed. To mount a label roll, and a supporting shaft therefor, in the frame arm 28 is pressed forwardly, compressing the spring tongue 32 and causing head 29 to rock slightly relatively to bar 13 as shown in Fig. 6 until aperture 34 registers with apertures 22, whereupon shaft 23 is passed through the bearing apertures in arms 20 and 28 and through core 26 of the label roll. Core 26 preferably fits loosely on the shaft or pencil 23 as shown in Fig. 8, so as to revolve freely thereon, and the rod or pencil preferably fits snugly in its bearing apertures 22 and 34.

As arm 28 tends to spring back to its normal position, it exerts transverse pressure on shaft 23 and thus frictionally holds the shaft against accidental endwise displacement and also against rotation in its bearings or supporting apertures. Arm 28 and arms 20 are formed of thin and inherently resilient sheet metal and are therefore laterally flexible. This assists in preventing accidental endwise movement of the shaft as such movement, owing to friction in the bearing apertures, tends to flex the arms laterally and thus causes a cramping action of the arms on the shaft 23.

Spring tongue 32 also serves to frictionally hold the arm 28 in adjusted position on bar 13, and said arm is preferably adjusted longitudinally of bar 13 to lightly clamp the label roll 27 between said arm and the arm 20 which depends from frame bar 16, as shown in Fig. 3. The label roll is thus frictionally held against accidental

unrolling as well as against a too free rotary movement when the web 27 is fed through the paper feed devices of the machine. Web 27 is led from the roll over the rounded guide flange 18 on the roll-holding frame to the paper table 3, and is fed around the platen to the printing point by the usual paper feed mechanism and line space mechanism of the machine.

When two or more rolls of labels are mounted on shaft 23, one or more additional detachable arms 28 are employed, the additional roll or rolls being each clamped between two of the arms 28, as indicated in dotted lines in Fig. 3, so that the several webs may be fed in unison or independently to the printing point.

What I claim is:

1. The combination with a typewriting machine having a traveling carriage, of a paper roll supporting shaft, end and intermediate shaft-carrying members movable in unison with the carriage, and means whereby said intermediate and end members exert pressure on the shaft transversely of said shaft.

2. The combination with a typewriting machine having a traveling platen carriage, relatively yieldable end and intermediate shaft supports mounted on the carriage and provided with shaft bearings, the bearing on the intermediate support being normally out of register with the bearings in the end supports, and a straight paper-roll-supporting shaft extending through all of said bearings.

3. The combination with a typewriting machine having a traveling carriage, of a frame detachably held to the carriage, a pair of end shaft supports and an intermediate shaft support on the frame having apertures therein, means whereby said intermediate and end supports may be sprung relatively to each other to bring said apertures into axial alignment, and a straight paper-roll-supporting shaft extending through said apertures and held against endwise movement by the binding action of the relatively springy supports.

4. A paper-roll holder for typewriting machines comprising a frame adapted for attachment to a platen carriage and provided with end bearings for a roll-supporting shaft, and a member carried by the frame intermediate said end bearings and spring-urged transversely of the axial line of said end bearings, said member having a shaft bearing normally out of register with the end bearings.

5. A paper-roll-holding attachment for typewriting machines comprising a frame having end bearings for a roll-supporting shaft, and a member yieldably held to the frame and adjustable longitudinally of the frame between said end bearings, said mem-

ber having a shaft bearing normally urged out of register with the end bearings.

6. The combination with a typewriting machine having a traveling platen carriage, of a frame supported on the carriage having shaft-bearings at its ends, a shaft supported in said bearings, and a member slidably and yieldably connected with the frame for adjustment longitudinally of the shaft and provided with a shaft bearing, the yielding connection between said member and frame normally tending to shift the bearing on said member out of register with the end bearings.

15 7. The combination with a typewriting machine having a traveling platen carriage, of a paper-roll-supporting shaft, end supports for the shaft movable with the carriage, and an intermediate member movable with the carriage having a bearing aperture for the shaft and spring-urged transversely of said shaft.

8. The combination with a typewriting machine having a traveling platen carriage, of a paper-roll-supporting shaft, and a plurality of laterally flexible shaft supports movable with the carriage and provided with apertures through which said shaft extends, one of said supports being spring-urged transversely of the shaft.

35 9. The combination with a typewriting machine having a traveling platen carriage, of a pair of laterally swinging arms pivotally supported at their forward ends on the carriage and foldable into compact relation with the carriage, and a detachable paper-roll holder having apertures through which said arms slidably extend.

40 10. The combination with a typewriting machine having a traveling platen carriage, of a pair of laterally swinging arms pivotally supported at their forward ends on the carriage and foldable into compact relation with the carriage, said arms being tapered toward their free ends, and a detachable paper-roll holder having apertures therein adapted to receive the free ends of said arms and bind on the arms when the holder is shifted toward the pivoted ends of the arms.

55 11. The combination with a typewriting machine having a traveling platen carriage, of a pair of laterally swinging arms connected at one end with the carriage, stops for limiting the swinging movement of the free ends of the arms away from each other, said arms having inner cam edges, and a detachable paper-roll-holder having slots therein adapted to receive the arms and cam the free ends of said arms apart until arrested by said stops.

60 12. A paper-roll holder for typewriting machines comprising a rectangular sheet metal frame adapted for attachment to a platen carriage and having one longitudinal

member thereof formed with a curved paper-guiding flange, integral arms depending from the end members of the frame provided with axially aligned apertures, an arm slidably held at one end to the other longitudinal member of the frame intermediate said integral arms and having an aperture therein, and a paper-roll supporting shaft extending through said apertures in the three arms.

75 13. A paper-roll holder for typewriting machines comprising a rectangular sheet metal frame adapted for attachment to a platen carriage and having one longitudinal member thereof formed with a curved paper-guiding flange, integral arms depending from the end members of the frame provided with axially aligned apertures, and an arm slidably adjustable along the other longitudinal member of the frame and rockable transversely of said member, said adjustable arm having an aperture therein adapted to register with the apertures in the integral arms, a straight paper-roll supporting rod extending through the apertures in the three arms, and spring means normally tending to rock said adjustable arm and shift the aperture therein out of register with the apertures in the integral arms.

90 14. A label roll holding attachment for typewriting machines comprising a frame provided with fixed shaft supporting arms adjacent its ends, and an adjustable intermediate arm slidably and yieldably held to said frame intermediate the fixed arms, a roll-supporting shaft, said arms having shaft-receiving openings therein, and said adjustable arm cooperating with one of said fixed arms to hold rolls of different lengths against endwise movement on said shaft and being yieldable transversely of the shaft to cooperate with both of said fixed arms to hold the shaft against endwise movement.

95 15. A label roll holding attachment for typewriting machines comprising a one-piece rectangular sheet metal frame provided with integral shaft supporting arms adjacent its ends, an intermediate arm slidably held to one longitudinal member of said frame intermediate the integral arms, said arms having shaft-receiving openings therein, and spring means for frictionally holding said slidable arm in adjusted position whereby said arm is adapted to hold a label roll against one of the integral arms.

100 16. A label roll holding attachment for typewriting machines comprising a one-piece rectangular sheet metal frame provided with integral shaft supporting arms adjacent its ends, an intermediate arm slidably and rockably held to one longitudinal member of said frame intermediate the integral arms, said arms having shaft-receiving openings therein, and spring means for frictionally holding said slidable arm in

slidably adjusted position on its supporting member and normally shifting said arm transversely of said member to hold the opening in the slidable arm out of register with the openings in the integral arms.

17. The combination with a typewriting machine, having a traveling platen carriage, of means carried by said carriage for detachably and frictionally gripping a pencil at longitudinally spaced points to hold said pencil against endwise and rotary movements, and a label roll rotatably mounted on said pencil.

18. The combination with a platen carriage for writing machines having a paper table thereon, of means detachably connect-

ed with the paper table for supporting a pencil at the rear of said table parallel with the platen and frictionally holding said pencil against endwise and rotary movements, and a roll of paper rotatably supported on said pencil.

19. A label-roll holding attachment for typewriting machines, comprising a frame, a roll-supporting pencil, and relatively yieldable means on the frame for holding the pencil by a cramping action at longitudinally spaced points against endwise movement.

In testimony whereof I hereunto affix my signature.

HAROLD McD. BROWN.
